SANDAL

Jumpei Kurata, 1160-2 Mii-machi, Kurume City, Japan

Filed May 18, 1960, Ser. No. 60,636

Term of patent 14 years

(Cl. D7—7)

FIG. 1

FIG. 2

FIG. 3

The characteristic feature of the design resides in the contour of the sole.

I claim:

The ornamental design for a sandal, substantially as shown and described.
